(57) **CLAIM**

The ornamental design for a paint spray and roller container, substantially as shown and described.

DESCRIPTION

FIG. 1 is a right side perspective view of a paint spray and roller container showing our new design.

FIG. 2 is a top view thereof.

FIG. 3 is a bottom view thereof.

FIG. 4 is a front elevation thereof.

FIG. 5 is a back elevation thereof.

FIG. 6 is a left side elevation thereof; and,

FIG. 7 is a right side elevation thereof.

The broken lines shown in the drawings are for illustrative purposes only and form no part of the claimed design.
